UNITED STATES PATENT OFFICE

2,416,589

SHOE CLAMP

Joseph Millar, Winnipeg, Manitoba, Canada

Application September 7, 1945, Serial No. 614,971

4 Claims. (Cl. 12—123)

1

The present invention relates to new and useful improvements in clamps for holding boots or shoes in a convenient position while polishing the same.

An important object of the present invention is to provide a shoe clamp of this character adapted for use either as a fixed support when attached to a wall or other suitable supporting structure for firmly holding the shoes in a desired position while shining the same, or in which the device may be used as a portable shoe support for mounting on the knees of a person while shining the shoes.

A further object of the invention is to provide a shoe clamp of this character which may be folded into compact form when not in use.

A still further object of the invention is to provide a device of this character of simple and practical construction, which is strong and durable, efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which—

Figure 1 is a side elevational view.

Figure 2 is a top plan view with parts broken away and shown in section.

Figures 3 and 4 are fragmentary sectional views taken respectively on the lines 3—3 and 4—4 of Figure 2.

Figure 5 is a side elevational view showing the clamp in its folded position.

Figure 6 is a sectional view taken on a line 6—6 of Figure 1.

Figure 7 is a transverse sectional view of the clamping arm taken on the line 7—7 of Figure 1, and

Figure 8 is a side elevational view showing the device supported on the knees of a person while shining the shoe.

Referring now to the drawings in detail, wherein, for the purpose of illustration, I have disclosed a preferred embodiment of my invention, the numeral 5 designates a base generally which includes a fixed inner section 6 and a pivoted outer section 7 including a pair of rearwardly projecting apertured ears 8 projecting from the rear edge of the pivoted section and received in notches 9 in the front edge of the fixed section 6

2

and pivotally connected thereto by means of a transversely extending pin 10.

The upper surface of the pivoted section 7 is formed with a raised, transversely extending stop 11 adapted for engagement by the heel 12 of a shoe, slipper or the like 13 when supported on the base 5 in the manner as illustrated in Figure 1 of the drawing.

A post 14 is attached at its lower end to the rear edge of the fixed section 6 of the base and rises therefrom and formed with a forwardly curved upper end 15. A clamping arm 16 is pivotally attached to the front, upper end of the post 14 by means of a pin 17, the arm having a rearwardly curved upper end 18 positioned at one side of the curved upper end 15 of the post.

To the lower end of the arm 16 is attached a pad 19 adapted for positioning within the shoe 13 for bearing against the arch portion thereof.

The lower edge of the upper end 18 of the arm 16 is formed with a notch 20 adapted for receiving the angular end 21 of a link 22 pivoted at its other end to a cam 23 which is pivoted to the upper portion of the post 14 by means of a pin 24. The cam includes a handle 25 for raising and lowering the cam into a position for releasing the arm 16 to permit raising of the pad 19 into position as shown by the dotted lines in Figure 1 of the drawing, or for exerting a downward pressure on the pad 19 to firmly clamp the shoe in position on the base 5, as shown by the full line position in Figure 1 of the drawing.

The ears 8 are rounded, as illustrated more clearly in Figure 2 of the drawing, to facilitate folding of the front section 7 of the base into an upright position, as illustrated in Figure 5, into a compact form, when not in use, and the straight confronting edges of the sections 6 and 7 of the base limit the downward swinging movement of the section 7 so as to provide a rigid support for the shoe when the device is in its open position.

The upper surface of the pivoted front section 7 of the base is formed with a longitudinally extending slot 26 to receive the arm 16 when the device is in its folded position.

The transversely extending stop member 11 is formed with a kerf 27 at its rear edge to receive a strap 28 for attaching the base on the knee of a person while shining the shoe clamped on the base, thus to enable use of the device as a portable shoe clamp. It will also be apparent that the base 5 may be attached to a wall or other suitable supporting structure, if desired, for permanently attaching the clamp in position.

In view of the foregoing description taken in conjunction with the accompanying drawings, it is believed that a clear understanding of the construction, operation and advantages of the device will be quite apparent to those skilled in this art. A more detailed description is accordingly deemed unnecessary.

It is to be understood, however, that even though I have herein shown and described a preferred embodiment of my invention that the same is susceptible to certain changes fully comprehended by the spirit of the invention as herein described and the scope of the appended claims.

Having thus described the invention, what I claim as new is:

1. A shoe clamp comprising a base adapted to support a shoe thereon, a post rising from the base, a clamping arm pivoted to the post and having one end arranged to enter the shoe to clamp the shoe on the base, and a locking device carried by the post and adapted for engaging the other end of the arm to exert a clamping pressure on the shoe-engaging end of the arm.

2. A shoe clamp comprising a base adapted to support a shoe thereon, a post rising from the base, a clamping arm pivoted to the post and having one end arranged to enter the shoe to clamp the shoe on the base, a lever pivoted on the post, and means connecting the lever to the other end of the arm and adapted to exert a clamping pressure on the shoe-engaging end of the arm.

3. A shoe clamp comprising a base adapted to support a shoe thereon, a post rising from the base, a clamping arm pivoted to the post and having one end arranged to enter the shoe to clamp the shoe on the base, means for locking the arm in its clamping position, and a strap engaging the base for securing the base on a supporting member.

4. A shoe clamp comprising a base including a foldable sectional base adapted to support a shoe thereon, a transverse stop on the base forming an abutment for the heel of the shoe, a post rising from the back of the base, a clamping arm pivoted to the post, a pad on one end of the arm adapted to enter and bear against the shoe, and means carried by the post and connected to the other end of the arm for exerting clamping pressure thereon.

JOSEPH MILLAR.
